UNITED STATES PATENT OFFICE.

JOHN E. CONZELMAN, OF ST. LOUIS, MISSOURI, ASSIGNOR TO UNIT CONSTRUCTION COMPANY, OF ST. LOUIS, MISSOURI, A CORPORATION OF DELAWARE.

CONCRETE CONSTRUCTION.

992,734.

Specification of Letters Patent. Patented May 16, 1911.

Application filed April 14, 1910. Serial No. 555,355.

To all whom it may concern:

Be it known that I, JOHN E. CONZELMAN, a citizen of the United States, residing at the city of St. Louis, State of Missouri, have 5 invented certain new and useful Improvements in Concrete Construction, (Case L,) of which the following is a specification, reference being had therein to the accompanying drawings.

- 10 This invention relates to concrete construction in which concrete slabs rest on concrete beams or other supports and are themselves united to form a rigid and unitary structure.
- 15 An object of the present invention is to provide means for uniting adjacent slabs so that the adjoining edges of each are locked securely together.

A further object of this invention is to 20 provide reinforcement for connecting the uniting means between a pair of slabs that rest on one side of a beam or support with the uniting means between a pair of slabs that rest on the opposite side of said beam 25 or support.

In the drawings forming part of this specification, in which like numbers of reference denote like parts wherever they occur, Figure 1 is a perspective view showing two 30 pairs of slabs resting on a beam, a part of the beam and two of the slabs being broken away to show the formation of the edges of the other two slabs; Fig. 2 is a sectional view on the line 2—2, Fig. 1; Fig. 3 is a sectional view on the line 3—3, Fig. 1; and Fig. 4 is a perspective view of part of the concrete key that is formed between two adjoining slabs.

Each slab 1 is molded with any desired 40 configuration.

The beam 2 is preferably formed with substantially the same shape in cross-sectional configuration as the beam disclosed in my copending application Serial No. 45 528,298, filed November 16, 1909. Said beam is provided with a pair of shoulders 3 and a tenon 4. A flange 5 of slab 1 rests on a shoulder 3 and against tenon 4. Said flange 5 raises the top surface of slab 1 to a greater 50 distance above shoulder 3 than the distance the tenon 4 projects above said shoulder, so that, when a slab is placed upon each shoulder 3 of beam 2, a space 6 above tenon 4 is left between the two slabs supported by said 55 beam.

Each edge of slab 1 that is disposed at an angle to shoulder 3 of beam 2 is provided with a groove 7 and a groove or grooves 8, groove 7 being preferably arranged to extend the entire length of said edge, and 60 groove 8 being located above groove 7 in order to communicate with space 6 and arranged to extend only a short distance of the length of said edge. When two slabs are placed upon one shoulder 3 of a beam 65 2, a crack 9 is left between the adjoining edges of said slabs and the grooves 7 and 8 of one slab register with the grooves 7 and 8, respectively, of the other slab. When another pair of slabs 1 is similarly placed upon the other shoulder 3 of said beam, the crack 9 between said pair of slabs aligns with the other crack 9 between said two slabs. Boards or formers (not shown in the drawings) are placed underneath cracks 9, and grout or 70 similar cement mixture or wet concrete is poured into space 6 and, also, upon said boards or formers and into cracks 9. The grout or other mixture in space 6 and cracks 9 is leveled off flush with the surface of said 75 slabs, and, when it sets, unites said slabs and beam 2 integrally together. When the grout or other mixture is poured into a crack 9, it fills grooves 7 and 8, and, when it sets, forms a cement or concrete key 10 with tongues 11 80 and 12 projecting into grooves 7 and 8, respectively, and unites the adjoining edges of slabs 1 forming said crack integrally together.

As an additional strengthening means a 90 reinforcing bar 13 is embedded in grooves 8 in one crack 9 and is arranged to extend over beam 2 and project into the grooves 8 in the other crack 9 in order to tie the cement or concrete keys in said cracks firmly together and, also, to hold the slabs 1 snugly 95 against tenon 4. Bars 14 lie near the bottom surface of each slab to prevent sagging and extend preferably in both directions in said slab. Adjacent their ends each bar 14, turns 100 upwardly and extends near the top surface of said slab. The ends of said bars 14 extend downwardly into flange 5 in order to support a bar or bars 15 embedded in said flanges.

I claim:

1. A concrete structure comprising a beam, slabs arranged in pairs on opposite sides of said beam and having their top faces extending above the beam top to form 110

a space between the same above said beam, each pair of slabs on the same side of the beam having grooves in the adjoining side edges thereof and forming a crack between 5 the same, concrete keys integrally uniting said pairs of slabs and occupying the cracks between the same and having tongues extending into and integrally uniting with said grooves, a tie-rod extending over said 10 beam and connecting a tongue of one of said keys with a tongue of the other one of said keys, and a concrete filler for said space adapted to set integrally with said keys, said beam, and the edges of said slabs 15 surrounding said space.

2. A concrete structure comprising a beam, slabs on opposite sides of the beam, the slabs on the same side of the beam and on their adjoining faces being formed with 20 registering grooves, and being spaced apart at their adjoining faces to form cracks, a tie rod which extends across the top face of the beam and which has its end portions disposed in the said grooves, and a concrete 25 key filling each of the cracks, said concrete keys being formed with outwardly extending tongues on their opposite sides which align with the tie rod, the latter being embedded in the keys, said tie rod connecting 30 the keys, which latter are disposed on opposite sides of the beam.

3. A concrete structure comprising a beam, slabs on opposite sides of the beam supported thereby and having their top 35 faces extending above the top face of the beam, the slabs on the same side of the beam having their adjoining ends spaced apart to form cracks on opposite sides of the beam, a tying element extending across the beam 40 and into each of said cracks, and a cement key filling each of the cracks, and surrounding said tying element and a grout filling above the beam engaging between the projecting portions of the slabs.

45 4. A concrete structure comprising a beam, slabs on opposite sides of the beam supported thereby and having their top faces extending above the top face of the beam, the slabs on the same side of the beam having their adjoining ends spaced apart to form cracks on opposite sides of the beam, a tie rod which is disposed in 50 said space and which is located above the beam and has its end portions extending on 55 opposite sides of the beam, a concrete key

in each crack, and a concrete filler on the beam which surrounds the tie rod and is made flush with the top faces of the slabs.

5. A concrete structure comprising a beam, slabs on opposite sides of the beam 60 the slabs on the same side of the beam having their adjoining ends spaced apart to form cracks on opposite sides of the beam and being further formed with spaced longitudinal registering grooves, a tie rod 65 in one of the grooves extending across the beam and serving to tie the opposite slabs together, and a concrete key in each of the cracks surrounding the tie rod and filling the registering grooves. 70

6. A concrete structure comprising a beam, slabs on opposite sides of the beam, the slabs on the same side of the beam having their adjoining ends spaced apart to form a crack on each side of the beam and 75 being formed with registering grooves, the slabs having their top faces projecting above the top face of the beam, a tie rod extending above the beam and on opposite sides of the latter and into the registering 80 grooves of the slabs, a concrete key for each crack, said keys surrounding the end portions of the tie rod and extending into said registering grooves to fill the latter, and a concrete filler overlying the beam and 85 formed flush with the top faces of the slabs, said concrete filler completely surrounding the central portion of the tie rod.

7. A concrete structure comprising two pairs of slabs, the slabs of each pair being 90 arranged in side by side relation and the pairs being arranged opposite to each other and having their vertical end faces disposed in spaced relation, the respective adjacent vertical end faces of each pair of slabs being formed with spaced registering grooves, a tie rod disposed in one of the registering 95 grooves extending across the space between the two pairs of slabs and connecting both pairs of slabs, and a concrete key filling 100 said space between the two pairs of slabs and surrounding the tie rod, said key having tongues which extend into the registering grooves.

In testimony whereof I have affixed my 105 signature in presence of two witnesses.

JOHN E. CONZELMAN.
